UNITED STATES PATENT OFFICE.

GEORGE I. KING, OF DETROIT, MICHIGAN, ASSIGNOR TO THE AMERICAN CAR AND FOUNDRY COMPANY, OF ST. LOUIS, MISSOURI.

OPERATING MECHANISM FOR CAR-DOORS.

SPECIFICATION forming part of Letters Patent No. 663,031, dated December 4, 1900.

Application filed September 4, 1900. Serial No. 28,900. (No model.)

To all whom it may concern:

Be it known that I, GEORGE I. KING, a citizen of the United States, residing at the city of Detroit, in the State of Michigan, have invented a certain new and useful Improvement 5 in Operating Mechanism for Car-Doors, of which the following is a full, clear, and exact description, such as will enable others skilled in the art to which it appertains to make and 10 use the same, reference being had to the accompanying drawings, forming part of this specification, in which—

Figure 1 is a top plan view of the underframing of a car, the flooring being removed to 15 more clearly show my improved door-operating mechanism. Fig. 2 is a vertical longitudinal sectional view on line 2 2, Fig. 1. Fig. 3 is a transverse sectional view on line 3 3, Fig. 1. Fig. 4 is a transverse sectional view 20 on line 4 4, Fig. 1; and Fig. 5 is an inverted plan view of one of the doors.

This invention relates to a new and useful improvement in operating mechanism for car-doors, being designed particularly for use in 25 connection with doors which swing downwardly to open the exit for the load arranged in the floor of a car.

In the accompanying drawings I have 30 shown a construction of gondola-car such as is illustrated and described in an application filed by me May 7, 1900, Serial No. 15,817, for which construction my improved door-operating mechanism is especially designed; but it is obvious that there may be other constructions to which my present invention may 35 be applied.

The object of my present invention is to provide mechanism to control oppositely swinging doors arranged in the floors of the 40 cars, whereby said doors may be opened and closed simultaneously, and when closed may be locked in such position by a single locking device.

With this object in view the invention 45 consists in the employment of drums, sheaves, and chains or cables for operating the doors, all as will hereinafter be described and afterward pointed out in the claims.

In the drawings I have shown the center 50 sills 23 as being most widely separated in the middle of the car, said sills being in the form

of channels and forming the side walls of the opening in the floor of the car.

32 represents the cross-tie channels secured to the center sills, said cross-channels forming the end walls of the opening.

1 and 2 indicate a pair of doors hinged, respectively, to the center sills through the medium of suitable brackets. These doors are preferably braced by U-shaped frames 3, 60 whose ends form the hinge-eyes for the door, while the closing edges of each door are reinforced by angles 4, said angles being of such length as to extend beyond the cross-channels 32.

5 and 6 indicate chains or cables, which are secured to suitable eyes fastened to the projecting ends of the reinforcing-angles 4. These chains or cables 5 and 6 pass over a sheave 7, mounted in a suitable bracket 8, 65 secured to the cross-channel 32, after which said chains or cables merge into a single chain or cable and pass through the web of the center sill, and thence around a suitable sheave 9, mounted in a bracket secured to the 70 outer face of said center sill. From sheave 9 the chain or cable is wound upon a main drum 10, mounted upon a shaft 11, upon the outer end of which shaft is arranged the usual pawl-and-ratchet mechanism 12 and a squared 75 end or shank for receiving a wrench, whereby said shaft and drum may be rotated. This main drum 10, in addition to accommodating the chain or cable common to the chains or cables 5 and 6 above described, also accommodates a chain or cable which is wound in 80 the opposite direction and which passes around a sheave 9^a, thence through the center sill, where it is attached to divided ends 5^a and 6^a after passing over a sheave 7^a, mounted 85 in a bracket 8^a. The ends 5^a and 6^a are attached to eyes secured to the projecting ends of the reinforcing-angles 4, as before described.

To strengthen the reinforcing-angles, the planks at the closing edges of the door are 90 preferably extended coincident with said reinforcing-angles, as will be well understood by referring to Fig. 5.

In operating the doors where there is a load in the car it is only necessary to knock the 100 pawl out of engagement with its ratchet, when the weight upon the doors will cause

them to swing downwardly, thus rendering available the opening in the floor. In closing the doors it is only necessary to attach a wrench and wind the chains or cables on the 5 main drum, throwing the pawl into engagement with its ratchet to lock the doors in their closed position.

I am aware that minor changes in the arrangement, construction, and combination of to the several parts can be made and substituted for those herein shown and described without, in the least departing from the nature and principle of my invention.

Having thus described my invention, what 15 I claim, and desire to secure by Letters Patent, is—

1. The herein-described door comprising a U-shaped frame to which the panels of the doors proper are secured, and a reinforcing- 20 angle arranged along the closing edge of the door, said reinforcing-angle projecting beyond the edges of said panel proper; substantially as described.

2. The combination with oppositely-swing- 25 ing doors, of reinforcing-angles projecting beyond the ends thereof, chains or cables at-

tached to the projecting ends of said angles, sheaves over which said chains or cables pass, and a main drum upon which said chains or cables are wound; substantially as 30 described.

3. The combination with the center sills and cross-beams forming the side and end walls of an exit-opening, of doors hinged to said center sills, reinforcing-angles arranged 35 along the closing edges of said doors and projecting beyond said cross-beams, sheaves mounted upon said cross-beams, cables secured to said projecting ends of the reinforcing-angles, and passing over said sheaves, a 40 main drum around which said chains or cables pass, and a pawl-and-ratchet mechanism coöperating with said main drum; substantially as described.

In testimony whereof I hereunto affix my 45 signature, in the presence of two witnesses, this 4th day of September, 1900.

GEORGE I. KING.
